UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR PRINTING-TYPE.

SPECIFICATION forming part of Design No. 15,556, dated November 18, 1884.

Application filed September 29, 1884. Term of patent 7 years.

To all whom it may concern:

Be it known that I, HERMAN IHLENBURG, (assignor to MACKELLAR, SMITHS & JORDAN,) of the city and county of Philadelphia, Pennsylvania, have invented and produced a new Design for a Font of Printing-Type, of which the following is a specification.

The nature of the design is clearly shown in the accompanying typographic impression, to which reference is made; and it consists of an unshaded letter, as shown. The heavy triangular terminations are found at the top and bottom of the up-and-down portions of the A, B, D, E, F, H, I, K, L, M, N, P, R, T, U, V, W, X, Y, and Z. The cross-lines of the A and H are ornamented centrally by a heavy dot. The C is formed of the heavy curved portion, followed by the light curved line below, and terminating in the heavy triangular ornament above, upon the right. The cross-lines of the E, upon the right, terminate in the heavy triangular ornaments. The upper cross-line and lower cross-line of the F and L are similarly formed. The lower portion of the

G, upon the right, is concaved, its upper portion provided with the triangular termination. The lower portion of the O is ornamented by the scroll-like figure, followed by a curved line extended beyond the letter. The lower portion of the P, upon the right, is ornamented by a line curving to the left and terminating in a heavy dot, from which figure upon the right proceeds a curved line with dot termination. The tail of the Q consists of a curved line flattened out, having the heavy dot termination upon the left. In connection with the letters are shown a series of nine ornamental affixes, and reference is made to the typographic impression showing their exact configuration.

Having now described my invention, I claim as new—

The design for a font of printing-type, as shown and described.

HERMAN IHLENBURG.

In presence of—

C. F. HUCH,

HERMAN METIUS.
